UNITED STATES PATENT OFFICE

163,139

ACOUSTICAL TILE

Louis Romanelli, Chicago, Ill., assignor to Certain-Teed Products Corporation, Ardmore, Pa., a corporation of Maryland

Application November 18, 1949, Serial No. 6,130

Term of patent 14 years

(Cl. D68—1)

To all whom it may concern:

Be it known that I, Louis Romanelli, a citizen of the United States, residing at Chicago, in the county of Cook and State of Illinois, have invented a new, original, and ornamental Design for Acoustical Tiles, of which the following is a specification, reference being had to the accompanying drawing, forming part thereof.

In the drawing,

Fig. 1 is a front face view of an acoustical tile showing my new design; and

Fig. 2 is an edge view of said tile.

I claim:

The ornamental design for an acoustical tile, as shown.

LOUIS ROMANELLI.
